(57) **CLAIM**

The ornamental design for a rebound training device, as shown and described.

DESCRIPTION

FIG. 1 is a top, back, right side perspective view of a rebound training device showing my new design;

FIG. 2 is a front elevational view of the rebound training device shown in FIG. 1;

FIG. 3 is a right side elevational view of the rebound training device shown in FIG. 1;

FIG. 4 is a back elevational view of the rebound training device shown in FIG. 1;

FIG. 5 is a left side elevational view of the rebound training device shown in FIG. 1;

FIG. 6 is a top plan view of the rebound training device shown in FIG. 1;

FIG. 7 is a bottom plan view of the rebound training device shown in FIG. 1; and,

FIG. 8 is a top, back, right side perspective view of the rebound training device shown in FIG. 1 with the hand holds repositioned and a portion of the spring elements removed to illustrate a position of use.

1 Claim, 8 Drawing Sheets
